UNITED STATES PATENT OFFICE.

LOUIS DAVIS, OF NEW YORK, N. Y.

FLUID-MIXING ATTACHMENT FOR FAUCETS.

1,080,957.

Specification of Letters Patent.

Patented Dec. 9, 1913.

Application filed April 7, 1913. Serial No. 759,379.

To all whom it may concern:

Be it known that I, LOUIS DAVIS, of the city, county, and State of New York, have invented certain new and useful Improvements in Fluid-Mixing Attachments for Faucets, of which the following is a specification.

My invention relates to devices for mixing the fluids discharged from faucets and is especially applicable to hot and cold water faucets.

The object of my invention is to provide a cheap and easily attachable device for faucets or spigots which will mix the fluids by causing them to issue from one opening.

A further object of my invention is to provide a device which is readily adjustable to the variable distances between faucets or spigots both horizontally and vertically.

In the drawings, Figure 1 is a front view of one form of my invention. Fig. 1^a is a front view of my invention as it appears when adjusted to faucets placed a short distance apart. Fig. 2 is a front view and partial vertical section of another and the preferred form of my invention. Fig. 3 is a side view of the mixing ball attached to the fluid conducting coils, and Fig. 4 is a front view and partial vertical section of the same.

To the accomplishment of the aforesaid objects my invention consists in the peculiar novel construction, arrangement and combination of parts hereinafter described in the specification and more particularly pointed out in the claims, reference being had to the accompanying drawings forming a part of this specification wherein like numerals of reference denote like parts throughout the specification.

Referring more specifically to the drawings, 1 represents the faucets or spigots or pipes, which conduct the fluids, 2 are the caps, preferably made of metal, which are removably attached to the faucets 1 and are made to fit tightly around the said faucets 1, by means of the elastic members 3. Said elastic members 3 are secured to the hollow metallic cups 2, either by corrugations in said metallic cups 2 or in any other manner well known to the art. The diameter of the hole in the elastic member 3 being made slightly smaller than the diameter of the faucet, a water tight joint is readily effected by simply pushing the cap 2 over the

faucet 1. The said caps 2 are secured to the ends of the preferably helical coil 4, Fig. 1, and the coils 8 and 9, Fig. 2, which are made preferably of metal having a low elastic limit, such as lead or tin, so that the said coils 4, 8 and 9 will retain a permanent set when a slight tensile or compressive or bending stress is exerted thereon manually.

The fluids which enter at the ends of the coil 4 are mixed in the space above the outlet pipe 5 and are then discharged through the outlet pipe 5, which is attached at or near the central part of the coil 4. The outlet cap 10 may be screwed or otherwise fastened to the outlet pipe 5 to lengthen the discharge opening.

The coil may preferably be made of two parts 8 and 9 to allow the insertion of the ball 6 between the ends of the coils as shown in Figs. 2, 3 and 4, which allows the fluids to be more thoroughly mixed before issuing from the outlet by reason of the larger space in which the mixing occurs.

My device is intended to be used preferably in connection with the hot and cold water faucets in the ordinary house sink, wash tubs and bath tubs. The temperature of the water issuing from the outlet opening can easily be regulated by adjusting the faucets to vary the amounts of hot and cold water. I do not limit myself, however, to the mixing of hot and cold water as it is obvious that any fluids can be mixed in the same way in any desired proportion, if the fluids are first made to pass through separate faucets or spigots. The diameter of the coils 8 and 9 being smaller than that of the faucets, the velocity of the streams of fluids is greatly increased on entering the coils, with the result that, when the said streams of fluids enter the ball 6, they meet and become mixed due to their velocities and the mixture is discharged through the outlet opening.

When the distance between faucets is greater than is usual, the coil 4 can be stretched by a tensile pull and it will stay stretched as shown in Fig. 1. In the same manner, the coil can be compressed to fit the distance between faucets when the said distance is less than usual. When the faucets are not on the same horizontal line, the coil can be suitably bent to properly join the said faucets.

It can readily be seen that the outlet pipe

5 can be adjusted to various positions after my device is attached to the faucets, by means of a slight force exerted in the desired direction and the mixing ball 6 can 5 be adjusted in the same manner.

I do not limit myself to the specific form of construction shown herein, as it is readily seen that the form of the caps and outlet pipes can be changed without departing 10 from the scope of my invention.

What I claim is:

1. The combination with fluid conducting faucets, of metallic helical coils of pipe capable of fixed adjustment in length and 15 direction to fit between said faucets, means attached between said coils for mixing said fluids and means for discharging the fluids from said coils.

2. The combination with fluid conducting 20 faucets, of metallic coils of pipe capable of fixed adjustment manually in length and direction, a ball attached between said coils and an outlet pipe attached to said ball.

3. The combination with fluid conducting 25 faucets, of metallic helical coils of pipe capable of fixed adjustment manually in length and direction, means removably attached to said faucets for conducting the fluids to the outer ends of said coils, a ball 30 attached to the opposite ends of said coils and an outlet pipe attached to said ball.

4. The combination with hot and cold wa-

ter faucets, of a metallic coil of pipe of low elastic limit, capable of fixed adjustment in length and direction to fit between said faucets, means removably attached to said faucets for conducting the water to the ends of said coil, means for mixing the water attached near the central part of said coil and means for discharging the water from said 40 mixing means.

5. The combination with hot and cold water faucets, of metallic coils of pipe of low elastic limit capable of adjustment in length and direction to the space between said faucets, means removably attached to said faucets for conducting the water to said coils, a water mixing ball secured to the said coils, and means for discharging the water 45 from said ball.

6. The combination with hot and cold water faucets of metallic helical coils of pipe of low elastic limit capable of fixed adjustment in length and direction to fit between 50 said faucets, caps removably attached to said faucets for conducting the fluids to the outer ends of said coils, a water mixing ball secured to the opposite ends of said coils and an outlet pipe attached to said ball.

LOUIS DAVIS.
